UNITED STATES PATENT OFFICE.

RICHARD M. TEETSAL, OF ENDICOTT, NEW YORK, ASSIGNOR TO ENDICOTT JOHNSON CORPORATION, OF ENDICOTT, NEW YORK, A CORPORATION OF NEW YORK.

MEANS FOR ATTACHING RANDS TO HEELS.

Application filed May 14, 1924. Serial No. 713,193.

To all whom it may concern:

Be it known that I, RICHARD M. TEETSAL, a citizen of the United States, residing at Endicott, in the county of Broome and State 5 of New York, have invented certain new and useful Improvements in Means for Attaching Rands to Heels; and I hereby declare that the following is a full, clear, and exact description thereof, reference being 10 had to the accompanying drawings which form part of this specification.

This invention relates to the manufacture of composite or leather heels for boots and shoes and its object is to provide novel 15 means for holding the rands properly spread in the mold preparatory to being attached to the top lift of a heel. Heretofore the rands have been formed from a leather blank cut to a suitable shape and having its 20 central portion skived out so that the rand will be thinner at its inner edge than at its outer edge, such prepared leather blank being spread into an approximately horse-shoe shape, and customarily held in spread position by hand while being attached to the 25 heel. In applying such rands to heels by the well known Alsop heel building machine or other machines used for such purposes, it has been necessary for the operator 30 to spread the rand blank by hand and it is so expanded against the guard or guard edges of the heel mold until the rand is clamped against the heel by the presser.

The present invention provides a novel device, for use in connection with machines or 35 molds for applying rands to heels, whereby the rand blank may be spread and mechanically held in place in the mold preparatory to the application of pressure thereto.

I will explain the invention with reference to the accompanying drawings which 40 illustrate so much of a heel making mechanism or mold and the novel means and method of spreading the rand blank and applying the same to the heel, as will enable others skilled in the art to adopt and use the invention. In the claims are summarized the essentials of the invention and novel 45 features of combination and novel combinations of parts for which protection is desired.

In said drawings:

Figure 1 is a conventional perspective view of a part of the mold and part of the 50 presser of an Alsop heel building machine

equipped with my novel improvements for applying the rand to the heel.

Figure 2 is a vertical sectional view on the line 2—2, Figure 1.

Figure 3 is a similar sectional view showing the mold closed and pressure being applied. 60

Figure 4 is a similar section on the line 4—4, Figure 3.

Figure 5 is a view of a rand blank.

Figure 6 is a view of such rand blank as spread for attachment to a heel.

Figure 7 is a perspective view of such rand attached to a heel lift.

The rands R are usually formed of a piece 70 of leather cut in the shape shown in Figure 5 with the center portion thereof skived out, as indicated at r, so that it is thinner along the line r' than at the outer edges thereof. When this rand is applied to a 75 heel it is spread out as indicated in Figure 6, by its side portions being spread apart along the line r', Figure 5, so that the outer thicker portion of the rand will conform to the contour of the outer edge of the heel; 80 and when the rand is finally attached to the heel it will appear as indicated in Figure 7.

The heel mold 1 may be of any suitable construction, internally shaped to conform to the exterior contour of the heel; and 85 contacts with a presser 2 adapted to press the rand R onto a leather lift L placed in the mold. The rand R is usually placed in the mold by hand, spread apart by hand, and held by hand, until the pressure plate is 90 applied thereto.

In the present invention I provide the heel mold with a spreader which may be attached to the mold in any suitable manner being preferably hinged as indicated at 3^a. This 95 spreader has a triangular portion 3 which approximately conforms exteriorly to the form of the V-shaped space between the bifurcations of the spread-rand, as shown. When the spreader is turned down into the mold as indicated in Figures 2 and 3 the portion 3 comes between the bifurcations of the spread rand R and keeps them properly distended (as indicated in Figures 6 and 7) 100 while the pressure is being applied. The spreader may be provided with outwardly projecting ears 3^c at its free end to facilitate raising it out of, or lowering it into, the mold.

In practice a heel or heel lift L is placed 110

in the mold 1, then a rand R is placed in rand spread and in place while it is being the mold on top of the lift L, then the spreader 3 is lowered onto the rand and the bifurcations of the rand spread apart as indicated in Figure 7 on opposite sides of the portion 3 of the spreader, which holds the rand in its spread position, as indicated in Figures 2 and 3. While the rand is so held pressure is applied to the rand to cause it to adhere to the lift. The contact surface of either rand or lift is previously coated with glue or cement before the rand is placed on the lift, and only sufficient pressure is applied to insure that the glue or cement will bind the rand securely to the lift.

Preferably the presser plate 2 is formed with a projection 2^a on its under side, which projection is approximately of horse-shoe shape; the bifurcations of the projection are separated by V-shaped recess 2^b corresponding in contour to the V-shape of the part 3 of the spreader, said recess being adapted to receive the part 3 of the spreader when the presser plate is applied to the rand, as indicated in Figures 1, 2 and 3. At the apex of the recess 2^b in the projection 2^a is a transverse recess 2^c adapted to accommodate the lugs 3^c on the part 3 of the spreader. The projection 2^a on the presser foot is thinner on the outside than on the inside, so that its under surface will fit closely against the rand, which is thinner on the inside than on the outside. The part 3 of the spreader fits neatly into the recess in the part 2^a when the presser plate is in pressure applying position.

The spreader is preferably attached to the die, and the projection 2^a attached to the under surface of the presser plate 2, in such a manner that when the presser is brought down upon the die the part 3 fits into the recess 2^b and the part 2^a presses the rand firmly against the lift of the heel. The pressure of the part 2^b against the rand in the die causes the glue on the opposed surfaces of the rand and heel lift to hold the rand firmly in place.

The pressure is applied when the rand has been put in position in order to squeeze it firmly against the heel lift so that the glue will take effect, but pressure is not used for the purpose of squeezing the rand itself into the heel. The spreader 3 holds the rand in place but does not hold the heel. The heel or heel lift is held in position by the die in which it is placed preparatory to attaching the rand. The spreader spreads the rand and holds it spread while it is being attached, but does not itself press the rand against the heel. The use of mechanical means to hold a rand spread while being applied to the heel lift is the important feature of the invention; and the particular novel device shown for holding the

What I claim is:

1. In means for attaching rands to heels; a heel mold; a movable spreader adapted to spread and position a rand upon the heel lift; and a presser adapted to press the lift against the heel, said spreader having a depending portion on its under side adapted to enter the mold and engage inner edges of the rand and press the rand against the mold, said presser having a projecting portion recessed to accommodate the spreader.

2. In means for attaching rands to heels; a heel mold; a movable spreader adapted to spread and position a rand upon the heel lift; and a presser adapted to press the lift against the heel, the spreader being provided with projections on its apex whereby it may be raised or lowered.

3. In apparatus of the character specified, a heel mold; a movable spreader adapted to spread and position a rand upon the heel lift; and a presser adapted to press the lift against the heel, said presser having a recess to accommodate the spreader; said spreader being hinged to the face side of the mold and provided with projections on its apex whereby it may be raised or lowered.

4. Means for applying rands to heels; comprising a support for a heel lift; a triangular rand spreader adapted to hold a rand distended when the latter is placed in the mold; and a presser adapted to press the rand against the lift while the spreader is in the mold; said spreader having a projection on its under side adapted to enter the mold and engage the rand which presses against the lift; and said presser having a projecting portion recessed to accommodate the spreader.

5. Means for applying rands to heels; comprising a support for a heel or heel lift; a triangular rand spreader adapted to hold a rand distended when the latter is placed in the mold; and a presser adapted to press the rand against the lift while the spreader is in the mold; the spreader being hinged to the face side of the mold and provided with projections on its apex whereby it may be raised or lowered.

6. In apparatus of the character specified; a heel mold; a movable spreader adapted to spread and position a rand upon the heel lift; and a presser adapted to press the lift against the heel, the spreader being hinged to the face side of the mold and provided with projections on its apex whereby it may be raised or lowered; said presser having a depending portion adapted to engage the rand in the mold and provided with a recess to accommodate the spreader and its projecting portions while in the mold and during the pressing operation.

7. Means for applying rands to heels, comprising a support for a heel or heel lift; a triangular rand spreader adapted to hold a rand distended when the latter is placed in the mold; and a presser adapted to press the rand against the lift while the spreader is in the mold; the spreader being hinged to the face side of the mold and provided with projections on its apex whereby it may be raised or lowered; and a presser having a depending portion adapted to engage the rand in the mold and provided with a recess to accommodate the spreader and its projecting portions while in the mold and during the pressing operation.

8. In apparatus for attaching rands to heels; an angular spreader adapted to spread the rand upon the heel; and means to press the rand against the heel, said means having an angular recess to accommodate the angular spreader.

9. In apparatus for attaching rands to heels; a support for a heel lift; an angular spreader hingedly attached to the support

and adapted to spread and hold a rand in spread position upon the heel lift; and a presser adapted to press the rand against the heel, said presser having an angular recess to accommodate the spreader.

10. In apparatus of the character specified, a heel mold; a movable wedge-shaped spreader adapted to spread and position a rand upon the heel lift; and a presser adapted to press the lift against the heel, said presser having a wedge-shaped recess to accommodate the spreader.

11. Means for applying rands to heels; comprising a mold for a heel or heel lift; a triangular rand spreader hinged to the support and adapted to hold a rand distended when the latter is placed in the mold; and a presser adapted to press the rand against the lift while the spreader is in the mold, said presser having a recess to accommodate the spreader.

In testimony that I claim the foregoing as my own, I affix my signature.

RICHARD M. TEETSAL.
